DISPLAY MODULE FOR A BANK OF VENDING MACHINES

Eldor A. Kluge, Oak Lawn, Robert G. Kosirog, Hampshire, and Thomas H. Wiebe, Arlington Heights, Ill., assignors to Canteen Corporation, Chicago, Ill.

Filed Sept. 1, 1972, Ser. No. 285,889

Term of patent 14 years

Int. Cl. D6—06

U.S. Cl. D6—139

Fig. 1

Fig. 2

Fig. 3

Fig. 4

FIG. 1 is a front elevational view of a display module for a bank of vending machines showing our new design wherein the first and fourth panels are equal in width, the second and third panels are of equal width and the fifth is of a width different from the other pairs of panels, this panel being the widest;

FIG. 2 is a left side elevational view;

FIG. 3 is a top plan view;

FIG. 4 is a front and left side perspective view of a display module for a bank of vending machines showing a modified form of our new design wherein each of the panels is of different width, the center panel being the widest, and wherein the corners of the upper frame members are mitered;

FIG. 5 is a front elevational view thereof;

FIG. 6 is a top plan view thereof; and

FIG. 7 is a left side elevational view thereof.

We claim:

The ornamental design for a display module for a bank of vending machines, substantially as shown and described.
